UNITED STATES PATENT OFFICE

2,612,940

MEDICAL PRACTICE CHAIR WITH ADJUSTABLE LEG AND FOOTREST SUPPORTS

Norman E. Lauterbach, Newark, N. Y., assignor to Ritter Company, Inc., Rochester, N. Y., a corporation of Delaware

Original application July 2, 1946, Serial No. 680,983. Divided and this application October 1, 1949, Serial No. 119,095

6 Claims. (Cl. 155—171)

1

This invention relates to chairs of the variety adapted for use by the medical profession during examinations, treatments, and minor operations, one object of the invention being to provide an improved chair of such character having a more adjustable, convenient, and efficient construction.

Another object is to supply a chair of the nature described having a tilting foot rest frame provided with leg and foot rest sections adapted for adjustment to various positions to suit the varying positions and uses of the foot rest frame and chair.

Another object is to afford a chair having a construction such as described above in which leg and foot rest sections are releasably connected with a back rest section for movement with or independently of the latter.

Another object is to provide a chair of the character described in which the foot rest section is maintained in a horizontal position throughout its angular range of adjustment relative to the chair seat, as well as provisions for locating the foot rest at different levels to suit different patients in kneeling on the foot rests for certain examination work.

This application is a division of my copending application, Serial No. 680,983, filed on July 2, 1946, now Patent No. 2,558,143, granted June 26, 1951, Medical Practice Chair, to which reference may be had for parts disclosed but not claimed herein.

To these and other ends the invention resides in certain improvements and combinations of parts, all as will be hereinafter more fully described, the novel features being pointed out in the claims at the end of the specification.

In the drawings:

Fig. 1 is a side elevation of a chair embodying the present invention and arranged to support a patient in upright sitting position;

Fig. 2 is a side elevation of the same with parts of the seat broken away and arranged to support a patient in a substantially horizontal position;

Fig. 3 is an enlarged fragmentary detail view of a latching means shown in Fig. 2;

Fig. 4 is a side elevation with the back rest and head rest lying substantially in the plane of the seat and with the leg rest so arranged that the patient may kneel on it;

Fig. 5 is a side elevation with the back rest and head rest in the plane of the seat, the foot rest being folded under the leg rest and the stirrups extended and elevated;

Fig. 6 is an enlarged side elevation of the seat frame and the frame for supporting the leg and

2

foot rests and associated mechanism, partly broken away and partly in section;

Fig. 7 is an enlarged top plan view of the foot rest with the foot supporting section in raised position, and

Fig. 8 is a front elevation of the same.

The preferred embodiment of the invention herein disclosed, by way of illustration, comprises a chair having a circular base 40, Fig. 1, supporting an electric motor 41 and a housing 42 for hydraulic mechanism for raising and lowering a chair supporting column 43 which is mounted for rotation also in the housing, as well understood in the art. At 44 is a foot lever controlling the rotation of the chair and at 45 are foot levers for raising and lowering the chair. These parts for moving the chair column may have any known or suitable construction and form no part of the present invention.

10 The chair column carries at its top a generally circular supporting head 46 on which a seat frame 47 is supported by suitable means allowing it to have a controlled tilting movement. Seat frame 47 is a generally rectangular, hollow frame, on which the back rest, arm rests, and leg and foot rests are supported in connected relation with each other for movement together simultaneously to different adjusted positions.

15 The back rest 48 (Fig. 1) with its associated head rest is slideable longitudinally on a post 49 which is pivoted at 50 on the back of the seat frame 47, for tilting adjustment within the range from the upright position shown in Fig. 1 to the substantially horizontal position shown in Fig. 2.

20 The arm rest frames 51—52 have one end pivotally connected to the back rest and the other to the side of the seat frame, to suitably control the sliding movement of the back rest on post 49 and these arm rest frames have link connections

25 53 to 57, inclusive (Fig. 6) with a leg and foot rest frame, shown generally at 58, which is pivotally supported on a shaft 59 at the front end of the seat frame, the foregoing construction being the subject matter of said copending application.

30 The invention comprises the tilting frame 58 which is pivotally connected with the front end of the seat frame for supporting adjustable leg and foot receiving rests. To this end, shaft 59, Fig. 6, is mounted for rocking movement at its opposite ends in bearings in the sides of the seat frame. Mounted to rock independently on the shaft is a sleeve 60 to the opposite ends of which are fixed a pair of spaced arms 58a having upper ends of "goose neck" shape to avoid interference 35 with the front end of the seat frame. Arms 58a

are rigidly connected with each other, as by means of a cross bar 61, Fig. 6, and form a hinged frame of rigid construction for supporting the leg and foot rests, as hereafter described. Arms 58a are formed with outwardly projecting shoulders 62 adapted to strike the bottom of the sides of the seat frame and stop the foot rest frame in its lowermost position, as shown in Fig. 6. The means for pivotally elevating this frame by the pivotal lowering of the back rest of the chair will now be described.

Keyed to the ends of shaft 59, beyond the ends of sleeve 60, are a pair of cross arms 53 each having one end pivotally connected at 54 with a link 55 pivoted at its opposite end 56 to the outer end of an arm 57 keyed on the trunnions, 63, of the arm rests, so that the tilting movement of the back rest, imparted to the arm rests, as described above, is transmitted by the arm rests as a rocking movement of shaft 59, the arm rests serving in this arrangement as an actuating connection between the back rest and the foot rest frame.

The opposite or lower end of one arm 53 is pointed as at 64, Fig. 3, for engagement with the suitably shaped end 65 of a plunger 66 sliding longitudinally in a hole 67 in the adjacent arm 58a of the foot rest frame. Plunger 66 has its other end reduced in diameter to provide a chamber housing a coiled compression spring 68 (Fig. 3) tending to project the plunger into the path of movement of the actuating arm 53. Pivoted at 69 to the reduced end of the plunger is a link 70 having opposing surfaces 71 and 72. Pivot 69 is located nearer the surface 71 so that when the lever is turned to present that surface to the frame, plunger 66 is released for movement by its spring into the path of the actuating arm 53. Lever 70 may be turned, however, to present its other surface 72 to the frame arm 58a, thereby withdrawing the plunger into its bearing out of the path of the actuating arm 53, so as to disconnect the foot rest frame and leave it unaffected by the tilting movement of the back and arm rests.

For supporting the foot rest, arms 58a are connected at their lower ends by a shaft 73, Figs. 6 to 8, inclusive, on which are pivotally carried a pair of spaced arms 74 extending rearwardly from the main supporting frame 75 of a sectional foot rest indicated generally at 76. Means are provided, comprising a parallel motion linkage, for controlling the pivotal movement of the foot rest on its frame, so as to maintain it substantially horizontal, or parallel with the chair seat, in any tilted position to which the foot rest frame may be moved with the back rest, as may be seen by comparison of Figs. 1 and 2.

For this purpose the foot rest frame 75 has spaced rearwardly extending arms 77 carrying a shaft, or trunnions 78, arranged to be engaged in open notches 79 in the lower ends of a pair of spaced links 80 pivoted at their upper ends on trunnions 81 on lugs 82 on the frame seat. For maintaining the links 80 in position for engagement with the foot rest, a metal strap 83 has its ends fixed to the rear side of a cover plate 84 having ears 85 fixed by screws to the arms 58a. The intermediate portion of strap 83 is deflected to pass behind a rod 86 connecting the links 80 so as to hold the links in position for engaging the foot rest. Means are provided for releasably securing the links to the foot rest comprising a latch 87 pivoted at 88 to one of the links, and having a stop flange 89 at one end, and hooks 90

at the other for engagement with the shaft 78, to hold it in the end notches of links 80, the latches being urged to engaging position by a gravity arrangement or by springs, as desired. 5 The ends of the latches beyond their hook portions are preferably so shaped, as at 91, as to be cammed back to clear notches 79, by the engagement therewith of shaft 78, so that the foot rest may be latched to the links 80 without manual operation of the latches. The latch may be manually operated to release the foot rest for folding pivotally upwardly against the frame, as hereafter referred to.

The foot rest 76 comprises the supporting frame 75 forming its lower section, and a flanged plate 92 (Fig. 7) forming its upper section. The lower section 75 comprises a supporting plate 93, Fig. 8, having upwardly turned marginal flanges 94 providing a compartment for receiving the upper section in its lowermost position. The upper section 92 comprises a plate 95, covered by a sheet of rubber or other suitable composition, 96, for contact with the feet and has downwardly turned marginal flanges 97 adapted to fit within the flanges of the lower section. The upper section is adjustably supported on the lower section by means of inner and outer pairs of links 98 and 99 pivotally connected as at 100. The links of the inner pair are rigidly connected by cross bars 101 (Fig. 7), while the outer links are rigidly connected by cross bars 102. One end of each inner link is pivoted at 103 to the ends of an upstanding rib 104 on the lower section plate 93 and the opposite ends of the inner links and their connecting cross bar 101 have sliding contact with the under side of plate 95 of the upper section, being supported on a keeper bracket 105 and guided by engagement of a pin 106 in the cross bar with a slot in the keeper bracket, as shown. One end of each of the outer links 99 is pivotally connected at 107 to bracket arms 108 on the under side of plate 95 of the upper section. The cross bar 102 at the opposite ends of these links is formed with recesses 109 (Fig. 8) 40 for engagement with detents provided by the hardened wear heads 110 and 111 of studs 112 and 113 fixed in inclined surfaces formed on the plate 93 of the lower section.

The upper section of the foot rest is provided with clips 114 and 115 located at opposite ends of its front side. By lifting upwardly on clip 114 (Fig. 7), to raise the upper section, its links 99 are swung pivotally to cause the connecting cross bar 102 to ride over the detents 110 and 111 until the upper section is adjusted to a desired elevation, after which the release of the lifting clip allows the cross bar to drop and engage at its recesses 109 with the desired detent and thus support the upper section. To lower the upper section, clip 115 is first slightly raised to shift the weight of the upper section toward the supporting links 99 at its opposite end, thus causing the bar connecting these links to rise above the detents 110 and 111 and so release the upper section for depression to a lower position or in nested relation in the lower section.

The leg rest comprises a rectangular frame 116 (Figs. 4 and 6), surfaced by a cushioning pad 117 and having upwardly projecting lugs 118 fixed at opposite sides of its top. These lugs are pivotally connected with the ends of bars 119 (Fig. 6), which are slotted longitudinally as at 120 and having enlarged arcuate opposite ends 121. The slotted portions of the bars embrace studs 122, fixed to the side arms of the frame and the arcu-

ate edges at the ends 121 of the bars are adapted to rotate in contact with concentrically curved ribs 123 on the side arms of the frame, except that such rotation may be restrained by engagement of shoulders 124 (Figs. 4 and 6) on the bar edges with the forward ends of the ribs. It is evident from this construction that with the arcuate bar ends and shoulders 124 so engaged with ribs 123, the bars are latched against movement on their studs and the leg rest is pivotally suspended in position against the front of the leg rest frame, so as to be out of the way in the upright position of the chair, shown in Fig. 1, or to support the legs of the patient in the horizontal position of the chair, as shown in Fig. 2. Or, the leg rest may be first swung upwardly on its pivots and the foot rest released and folded upwardly and inwardly against the front of the frame and the leg rest then pivotally lowered to cover it, as shown in Fig. 5 in which position the leg rest serves also as a comfortable surface of contact when the operator assumes a position close to the front of the chair seat, as required in some examinations.

The leg rest may also be pressed upwardly to raise its bars 119 sufficiently to release their shoulders 124 from the ribs 123, after which the bars may be rotated and slid forwardly on their studs to allow the leg rest to be moved forwardly and downwardly and placed upon the foot rest in any elevation of the latter, as illustrated in Fig. 4, to form a comfortable kneeling surface for the patient. An additional pad 125 (Fig. 1), may be fixed at the top of the leg rest frame to supplement the pad 117. The foot and leg rests are thus provided with a wide variety of adjustments for adapting them to serve a variety of purposes. The foot rest retains a horizontal position throughout the range of angular adjustment of its frame on the chair seat, but it may be easily retracted against the frame when desired. When again extended to horizontal position, the foot rest will be engaged, regardless of the angular position of the frame on the seat, by the positive means for maintaining it horizontal or level. It also contains an extremely compact device for providing various levels for kneeling when the chair parts are arranged for rectal examination work.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A chair comprising a seat, a frame mounted for pivotal movement relative to said seat and having thereon a leg rest, a foot rest mounted for pivotal movement relative to said frame, and connections between said leg rest and frame for positioning said leg rest selectively on said frame or on said foot rest.

2. A chair comprising a seat, a frame mounted for pivotal movement relative to said seat, a foot rest pivotally mounted on said frame and foldable to an inactive position thereagainst, and a leg rest adjustably mounted on said frame and

movable to a position to cover said foot rest in said folded position thereof.

3. A chair comprising a seat, a frame mounted for pivotal movement relative to said seat, a foot rest adjustably mounted on said frame and movable to an inactive position folded thereagainst, said foot rest having a lower supporting section and an upper foot receiving section and connections between said sections for adjustably supporting said upper section at different elevations, a leg rest, and adjustable connections between said leg rest and frame for supporting said leg rest on said frame or on said upper foot rest section in different adjusted positions of said upper foot rest section.

4. A chair comprising a seat, a frame mounted for pivotal movement relative to said seat, a foot rest on said frame having a foot receiving portion supported for movement to different positions of varying elevation, a leg rest, and adjustable connections between said leg rest and frame whereby said leg rest may be supported in folded position on said frame or extended to position on said foot receiving portion of said foot rest in the different elevated positions thereof.

5. A chair comprising a seat, a frame mounted for pivotal movement relative to said seat, a foot rest on said frame, a leg rest, and link means having one end pivotally connected with said leg rest and the other end connected with said frame for pivotal and sliding movement relative thereto whereby leg rest may be pivotally supported whereby said leg rest may be pivotally supported on said foot rest.

6. A chair comprising a seat, a frame mounted for movement relative to said seat, a foot rest movably mounted on said frame, a leg rest, trunnion means on said frame, link means pivotally connected with said leg rest and provided with slot means for pivotally and slidably engaging said trunnion means, and means on said frame for latching said link means with said leg rest pivotally supported against said frame, said link means being adapted when unlatched to support said leg rest for movement to and from extended positions on said foot rest.

NORMAN E. LAUTERBACH.
